UNITED STATES PATENT OFFICE

HENRY W. PRATT, OF JERSEY CITY, NEW JERSEY, ASSIGNOR TO WILLIAM H. LUTTON COMPANY, A CORPORATION OF NEW JERSEY

GARDEN FRAME

Application filed April 3, 1929. Serial No. 352,067.

This invention relates in general to so-called garden frames, hot beds, etc., which include frames or walls surrounding a pit in which seeds and small plants are grown. 5 The tops of such garden frames, hot beds, etc., consist of a plurality of sashes made up of wooden frames and panes of glass, and usually the sashes are laid upon the tops of the walls transversely of the pit and are held down by stones or the like to prevent the wind from blowing the sashes away. Also, it is usually difficult to remove the sashes because of the lack of means for gripping or getting hold of the same. 10 One object of my invention is to provide a garden frame of the character described embodying novel and improved features of construction for locking the sashes in place, so as to prevent the sashes from being blown off or otherwise accidentally removed. 15

Other objects are to provide in a garden frame a novel and improved combination of hand-holds and locking means for the sashes, whereby the hand-holds and locking means may be manufactured of cast metal 20 so as to withstand hard usage and to be adapted for application to any sash; to provide such a combination of hand-holds and locking means which is simple and inexpensive in construction, and to obtain other advantages and results as will be brought out by the following description.

Referring to the accompanying drawings, in which corresponding and like parts are 25 designated throughout the several views by the same reference characters,

Figure 1 is a top plan view of a garden frame embodying my invention;

Figure 2 is a transverse vertical sectional view, taken on the line 2—2 of Figure 1;

Figure 3 is a sectional elevation, taken on the line 3—3 of Figure 2;

Figure 4 is a sectional perspective view, taken on the line 4—4 of Figure 1, and

Figure 5 is a transverse vertical sectional view, taken on the line 5—5 of Figure 1.

Specifically describing the illustrated embodiment of the invention, the reference characters 1 and 2 designate the side walls 45 of a hot bed, or garden frame upon the top

of which are arranged the respective metal sills 3 and 4. The walls are made of different heights, as clearly shown in Figure 2. Secured as by angles 5 to the sill 4 of the higher side wall 2, is an angle bar 6 which has one flange 7 in overlying relation to the sill 4. At equidistantly spaced points longitudinally of the sills 3 and 4 are secured T-irons 8 with the webs 9 thereof extending vertically upward and the bases 10 secured by 60 screws 11 to the respective sills 3 and 4. Between each two of the T-irons is arranged a sash which includes top and bottom rails 12 and 13 and side stiles 14 within which is arranged a pane of glass 15. The upper rail of 65 each sash is normally fitted beneath the flange 7 of the angle bar 6 and rests on the sill 4. The stiles of the sash rest on the base flange of the T-irons 8, and the base or bottom rail 13 of the sash rests on the sill 3. 70

Secured to the lower edge of the base rail of each shaft at each end thereof is a handhold and lock member 16 which includes a base portion 17 having an integral end lug 19 at substantially right angles to said base 75 portion, coextensive in width with the base portion and having a central opening 20 therein and a handhold flange 18 concentric with said opening and integrally extending at an angle to said base portion at one side 80 edge thereof. The member 16 is secured to the respective sash with the end lug 19 substantially parallel with the adjacent side stile 14 and preferably substantially flush with the outer side of the stile. The vertical web 9 of each T-iron is formed with an opening 21 corresponding to the opening 20 which when the sashes are applied to the frame aligns with the openings 20 in the adjacent lugs 19. A locking pin 22 is adapted to be passed through the openings 20 in adjacent sashes and the corresponding opening 21 in the T-iron, as clearly shown in Figure 3 of the drawings. It will be obvious that with 85 the locking pin 22 so arranged, the lower ends of the sash are positively held against the sill 3. At the same time, the upper ends of the sash are positively held under the flange 7 of the angle bar 6, and accordingly the sash 100

cannot be accidentally removed from the garden frame, as by the wind.

When it is desired to remove any one of the sashes, the corresponding locking pin 22 is pulled from the openings 20 and 21, after which the handholds 18 are gripped and the sash raised upwardly and simultaneously pulled outwardly from beneath the flange 7 of the angle bar 6.

To prevent loss of the locking pins 22 they may be formed with an eye 23 at one end, to which is connected one end of a chain 24, the other end of which may be connected to a bolt 25 secured in the sill 3.

The ends of the garden frame are composed of the sash 26 mounted on side sills 27 as usual, and the inside of each side sash has secured thereto an angle bar 28, the vertical flange 29 of which may be provided with an opening to receive the locking pin 22 of the end sash, as do the openings 21 of the intermediate T-irons 8.

Obviously instead of using the locking pin 22 I may attach a padlock to the openings 20 and 21, or pass a chain through the openings and lock the ends of the chain together.

It will be understood that the specific embodiment of the invention herein described is primarily for the purpose of illustrating the principles of the invention, and that the details of construction of the garden frame may be modified without departing from the spirit and scope of the invention which is defined by the appended claims when construed in the light of the prior art.

Having thus described the invention, what I claim is:

1. A garden frame comprising side and end walls, an angle bar extending longitudinally of one of said side walls with one flange secured to the top of said wall and the other flange disposed in spaced and substantially parallel relation to said top of the wall, a sash resting upon said side and end walls and having one end arranged beneath said flange of said angle bar, and means for locking the other end of said sash against being raised from the corresponding side wall.

2. A garden frame comprising side and end walls, an angle bar extending longitudinally of one of said side walls with one flange secured to the top of said wall and the other flange disposed in spaced and substantially parallel relation to said top of the wall, end bars connecting said side walls and each having a vertical web and a horizontal flange, a sash having its ends resting upon said side walls and its opposite sides upon said horizontal flanges of said end bars with one end arranged between said flange of said angle bar and the top of the corresponding wall, and means at the other end of said sash for locking it to said vertical webs of the end bars.

3. A garden frame comprising side and

end walls, an angle bar extending longitudinally of one of said side walls with one flange disposed in spaced and substantially parallel relation to the top of said wall, end bars connecting said side walls and each having a vertical web and a horizontal flange, a sash having its ends resting upon said side walls and its opposite sides upon said horizontal flanges of said end bars with one end arranged between said flange of said angle bar and the top of the corresponding wall, said vertical webs of the end bars having transverse openings adjacent the other end of the sash, a member secured to the second-mentioned end of the sash adjacent each side edge thereof and having an opening to align with said opening in the adjacent vertical web, and a locking member adapted to be passed through said openings to lock said second-mentioned end of the sash to said end bars.

4. A garden frame comprising side and end walls, an angle bar extending longitudinally of one of said side walls with one flange disposed in spaced and substantially parallel relation to the top of said wall, end bars connecting said side walls and each having a vertical web and a horizontal flange, a sash having its ends resting upon said side walls and its opposite sides upon said horizontal flanges of said end bars with one end arranged between said flange of said angle bar and the top of the corresponding wall, said vertical webs of the end bars having transverse openings adjacent the other end of the sash, a member secured to the second-mentioned end of the sash adjacent each side edge thereof and comprising a base portion secured to the sash, an end lug at right angles to said base portion formed with an opening to align with said opening in the adjacent vertical web, and a locking member adapted to be passed through said openings to lock said second-mentioned end of the sash to said end bars.

HENRY W. PRATT.
